Primary Examiner—Louis S. Zarfas*Assistant Examiner*—Robert A Delehanty(74) *Attorney, Agent, or Firm*—Westman, Champlin & Kelly, P.A.(57) **CLAIM**

The design for athletic shorts, as shown and described.

DESCRIPTION

FIG. 1 is a front view of athletic shorts embodying my new design;

FIG. 2 is a right side view thereof, the left side being a mirror image of the right side view;

FIG. 3 is a rear view thereof;

FIG. 4 is a top view thereof; and,

FIG. 5 is a bottom view thereof.

The broken lines showing of interior environmental structure of the shorts in FIGS. 4 and 5 of the drawing views form no part of the claimed design.

The crosshatch shading shown in the drawings is understood to indicate fabric.

The area of the waistband including vertical lines indicates the inclusion of elastic material, and the area of the waistband devoid of vertical lines indicates the inclusion of non-elastic material.
